Fig. 3

Fig. 1 is a plan view of a puffed textile fabric showing my new design;

Fig. 2 is a schematic sectional view of the fabric of Fig. 1 along the line 2—2;

Fig. 3 is a schematic sectional view of the fabric of Fig. 1 along the line 3—3.

Fig. 4 is a schematic sectional view of the fabric of Fig. 1 along the line 4—4.

The design is embodied in a textile fabric having a surface of raised puffs arranged as shown in Fig. 1. Threads, represented by the straight horizontal lines in Figs. 2 and 3, interlaced in the fabric, hold the puffs raised.

We claim:

The ornamental design for a puffed textile fabric, as shown and described.
